DESK TOP MANUAL CARD READER

Glenn R. Ekers, Camp Hill, Pa., assignor to
AMP Incorporated, Harrisburg, Pa.

Filed Oct. 21, 1963, Ser. No. 77,063

Term of patent 14 years

(Cl. D26—5)

Fig. 2

Fig. 3

FIGURE 1 is a perspective of a desk top manual card reader showing my new design;

FIGURE 2 is a front elevation of the reader of FIGURE 1;

FIGURE 3 is a side elevation of the reader of FIGURE 1 taken from the right side thereof.

The side of the machine not shown is substantially a mirror image of the side shown except for the omission of the control handle, while the rear of the machine, not shown, is substantially plain and unornamented.

I claim:

The ornamental design for desk top manual card reader, as shown and described.
